UNITED STATES PATENT OFFICE

119,931

DESIGN FOR A CAMERA

Henry O. Drotning, Rochester, N. Y., assignor to
Eastman Kodak Company, Rochester, N. Y., a
corporation of New Jersey

Application February 7, 1940, Serial No. 90,104

Term of patent 14 years

To all whom it may concern:

Be it known that I, Henry O. Drotning, a citizen of the United States of America, residing at Rochester, in the county of Monroe, State of New York, have invented, a new, original, and ornamental Design for a Camera, of which the following is a specification, reference being had to the accompanying drawing, forming a part thereof, in which:

Fig. 1 is a perspective view of a camera showing my new design, the camera having the finder hood folded to a closed position.

Fig. 2 is a perspective view of the camera shown in Fig. 1 but showing the back and bottom as well as a portion of the side of the camera.

Fig. 3 is a fragmentary view similar to Fig. 1 but with the finder hood shown in an open or picture-taking position, and

Fig. 4 is a bottom plan view of the camera shown in the preceding views.

I claim:

The ornamental design for a camera, as shown and described.

HENRY O. DROTNING.
